UNITED STATES PATENT OFFICE.

ELMER C. PRATT, OF MOUNT DOME, CALIFORNIA, ASSIGNOR OF ONE-THIRD TO CORLENA M. PRATT, OF MOUNT DOME, CALIFORNIA, AND ONE-THIRD TO ANDREW B. JENSEN, OF BARSTOW, CALIFORNIA.

COMBINED ORE AND ROCK CRUSHER AND PULVERIZER.

1,262,091.

Specification of Letters Patent.

Patented Apr. 9, 1918.

Application filed July 23, 1917. Serial No. 182,215.

To all whom it may concern:

Be it known that I, ELMER C. PRATT, a citizen of the United States, residing at Mount Dome, in the county of Siskiyou and State of California, have invented new and useful Improvements in Combined Ore and Rock Crushers and Pulverizers, of which the following is a specification.

My present invention pertains to ore crushing machines, and has for one of its objects the provision of a machine which while simple in construction is highly efficient in operation and is well adapted to withstand the rough usage to which machines of analogous character are ordinarily subjected.

Another object of the invention is the provision of a combined ore crusher and pulverizer of large capacity, and adapted to be expeditiously and easily adjusted to meet different conditions.

Another object is the provision of a machine of the character indicated provided with auxiliary means for pulverizing the material to a still greater extent after the material has passed between the cone and the shell or cylinder of the machine.

Another object is the provision of improved means for actuating the cone incidental to the rotation of the cylinder.

Other objects and advantages of the invention will be fully understood from the following description and claims when the same are read in connection with the drawings, accompanying and forming part of this specification, in which:

Figure 1 is a view, partly in elevation and partly in diametrical section of a machine constructed in accordance with my present invention.

Fig. 2 is an elevation, with parts in vertical section, and other parts broken away, taken at right angles to Fig. 1.

Fig. 3 is a plan view, on a reduced scale, of the machine, and:

Fig. 4 is a detail horizontal section showing the diagonal arrangement of the lower bearing bar between two of the frame uprights.

Similar numerals of reference designate corresponding parts in all of the views of the drawings.

The frame of the machine comprises four uprights 1, of angular form in cross section,

designed to be fixed at their lower ends to a suitable base, and a top section 2, interposed between and suitably fixed with respect to the uprights 1, as shown in Figs. 1 and 2.

Journalled in suitable bearings 3 on the top section 2 of the frame is a drive shaft 4, equipped with pulleys 5, either or both of which may be connected through belts with a suitable motor. The said shaft 4 is also provided with a sprocket gear 6, a beveled gear 7 and an eccentric 8, the latter being illustrated in Fig. 2.

Arranged between and suitably fixed to the frame uprights 1, at intermediate points in the height thereof, are rings 9 and 10, and disposed and rotatable within the said rings 70 is the upright cylinder 11 which is provided with a suitable lining 12 and breakers 13 thereon. The said cylinder is supported on anti-friction bearings 14, preferably balls as shown, which are interposed between circumferential projections 15 thereon and the before described rings 10. At 16 the cylinder 11 is equipped with a spur-gear annulus which is meshed with a pinion 17 on an upright counter shaft 18 which has a beveled pinion 19 at its upper end, intermeshed with the beveled pinion 7 on the shaft 4, to effect rotation of the cylinder from said shaft 4.

The location of the counter shaft 18 in plan is closely shown in Fig. 3, and by comparison of Figs. 1 and 3, it will be readily understood that the pinion 17 is arranged partly in front of the toothed annulus 16.

The lower bearing bar 20 is movable vertically between two diagonally-opposite frame uprights 1, and is provided with a central cup 21, also with threaded apertures 22, the latter to receive and engage the threads on the vertical adjusting shafts 23 which are journalled in the lower ring 10 95 and have hand wheels 24, superimposed on said ring 10 so as to enable the shafts to suspend the bearing bar 20 and the load carried thereby.

At 25 is an upright central shaft which does not revolve, and fixed to said shaft and disposed in the cylinder is a cone 26, having breakers 27. The said shaft 25 is supported in the cup 21 of bearing bar 20 and on a section of steel 28, superimposed on a cushion 29, of rubber or rubber composition. From this it follows that when the vertical adjusting shafts 23 are rotated the bar 20,

the shaft 25 and the cone 26 will be raised or lowered to nicely adjust the latter with respect to the cylinder 11 as conditions require. The upper end portion of the shaft 25 is angular, preferably rectangular, in cross-section and is disposed in a correspondingly-shaped opening in a reciprocatory bar 30 which is pivotally connected at 31 to an arm 32 carried by a strap 33 that is mounted on and actuated by the strap 8. Thus when the shaft 4 is rotated to rotate the cylinder 11 about its axis, the shaft 25 and the cone 26 thereon will be oscillated or swung to and fro in a vertical plane with a view to furthering the crushing and pulverizing of the ore and the progress of the same through the machine between the cone and the cylinder.

Brackets 40 are fixed on the top frame section 2 and made to extend laterally from the upper portion of the frame, and connected through swinging links 41 with the said brackets is a feed trough 42, the inner discharge end of which is connected through a link 43 with the bar 30, and hence when the shaft 25 and the cone 26 are reciprocated the trough 42 will also be reciprocated to accelerate the feed of ore placed therein between the cylinder and the cone at the upper ends thereof.

At 50 is a receptacle disposed to receive the crushed ore from between the lower ends of the cylinder and cone, and communicating with and extending laterally from the said receptacle is a chute 51 which is designed to conduct the crushed and pulverized ore to rolls 52, 53 for further pulverization. The bearings of the roll 53 are preferably cushioned by blocks 54, of rubber composition, and the roll 52 is driven from the shaft 4 through the medium of the sprocket gear 6 thereon, a sprocket gear fixed with respect to said roll 52, and a sprocket belt 55 connecting the said sprocket gears.

It will be gathered from the foregoing that an important advantage of my novel machine resides in the compactness and durability thereof.

Having described my invention, what I claim and desire to secure by Letters Patent, is:

1. A crushing machine, comprising a cylinder rotatable about its axis, a reciprocatory cone disposed in said cylinder, a drive shaft, means intermediate the drive shaft and the cylinder for rotating the latter by the former, and means intermediate the drive shaft and the cone for converting the rotary motion of the former into reciprocatory motion necessary to reciprocate the latter.

2. A crushing machine, comprising a

frame, a cylinder rotatable about its axis and supported in the frame, a reciprocatory cone disposed in said cylinder, a drive shaft, means intermediate the drive shaft and the cylinder for rotating the latter by the former, means intermediate the drive shaft and the cone for reciprocating the latter, a reciprocatory feed trough mounted on the frame, and a connection between the reciprocating means and said trough for oscillating the latter.

3. The combination in a crushing machine, of a frame, a drive shaft thereon, a reciprocatory cone having a shaft, a reciprocatory feed trough mounted on the frame and located at the opposite side of the cone shaft, with reference to the drive shaft, a connection between the drive shaft and the cone shaft for reciprocating the latter, and a connection between the first-named connection and the trough for reciprocating the latter.

4. The combination in a crushing machine, of a frame, a drive shaft mounted on the frame and having an eccentric, a reciprocatory cone mounted in the frame and having a shaft the upper portion of which is polygonal in cross-section, a strap mounted on said eccentric, a bar having a polygonal opening receiving said upper portion of the shaft and connected with said strap, and means for adjusting the cone vertically.

5. The combination in a crushing machine, of a frame, lateral brackets on the upper portion thereof, a reciprocatory trough, links connecting said trough with said brackets, a drive shaft mounted on the frame and having an eccentric, a reciprocatory cone mounted in the frame and having a shaft the upper portion of which is polygonal in cross section, a strap mounted on said eccentric, a bar having a polygonal opening receiving said upper portion of the shaft and connected with said strap, a connection between said bar and the feed trough, and means for adjusting the cone vertically.

6. The combination in a crushing machine, of a frame, a rotatable cylinder mounted therein, a vertically adjustable cone disposed in the cylinder and having a shaft, a vertically-movable bearing bar guided in the frame and in which the lower portion of the cone shaft is disposed, and vertically disposed adjusting shafts through which the said bar is suspended from the frame.

In testimony whereof I have hereunto set my hand in presence of two subscribing witnesses.

ELMER C. PRATT.
